UNITED STATES PATENT OFFICE.

WALTER S. MONTGOMERY, OF ARLINGTON, NEW JERSEY.

AUTOMATIC RELIEF AND CONDENSER VALVE.

SPECIFICATION forming part of Letters Patent No. 691,067, dated January 14, 1902.

Application filed May 15, 1901. Serial No. 60,368. (No model.)

To all whom it may concern:

Be it known that I, WALTER S. MONTGOMERY, a citizen of the United States, residing at Arlington, in the county of Hudson and State of New Jersey, have invented certain new and useful Improvements in Automatic Relief and Condenser Valves; and I do hereby declare the following to be a full, clear, and exact description of the invention, such as will enable others skilled in the art to which it appertains to make and use the same.

My invention relates primarily to steam-engines, has especial reference to valves used in condensing plants for automatically directing the exhaust-steam from the main engine either to the condenser or to the atmosphere, and consists in certain improvements in construction, which will be fully disclosed in the following specification and claims.

The prevailing practice in the use of automatic relief-valves in connection with condensers is to have the valve held to its seat by the pressure of the atmosphere on top of the valve while the vacuum is underneath the valve. Thus when the vacuum is lost from any cause it requires a slight pressure in the main engine exhaust-pipe to lift the ordinary so-called "relief-valve," and while the engine is exhausting to the atmosphere the valve is resting on the current of outgoing steam. Consequently if the engine is to run non-condensing for any length of time it is necessary to block or hold the relief-valve up by levers on the outside with weights attached or by screwing a bolt up underneath the valve or by various other means, and it is necessary to have an additional gate or other valve to shut off the steam from going to the condenser.

The object of this invention is to provide a valve to perform automatically both of these functions.

The valve is operated by fluid-pressure from the boiler, controlled by a plug-valve supplied with ports to direct the fluid to move the valve in opposite directions.

In the accompanying drawings, which form part of this specification, Figure 1 represents a vertical section, partly in side elevation, illustrative of my invention; Fig. 2, a horizontal section on line 2-2, Fig. 1, and showing the plug-valve in section and the remaining parts in plan; Fig. 3, a side elevation of a sec-

tion of the relief-valve case or body; and Fig. 4, an enlarged detail view, partly in section, showing the levers for operating the plug-valve.

Reference being had to the drawings and the designating characters thereon, 1 indicates the case or body of the relief-valve, which is secured to the upper end of a condenser-chamber 2 and is provided with a lower valve-seat 3, through whose ports or passages 4 exhaust-steam flows to the condenser, and an upper valve-seat 5 of the same or less diameter than the seat 3, through whose ports 6 steam is discharged to the atmosphere. The spider 7 supports a cylinder 8, secured thereto by a screw-threaded bolt 9, and is supplied with a fluid through a passage or duct 10 in one arm of the spider and a passage 11 in the body of the cylinder, as shown in Fig. 1. The spider 12 supports a piston 13, secured thereto by a screw-threaded bolt 14, and in the arm 15 of the spider is a passage or duct 16, and in the piston 13 is a passage 17, through which a fluid is supplied, and the valve-case is provided with an opening 18, to which the exhaust-pipe (not shown) is attached in any suitable manner, and a hand-hole 19, provided with a suitable cover. (Not shown.)

20 indicates the relief-valve, which is provided with a lower valve-face 21 and an upper valve-face 22, corresponding in diameter, respectively, with the lower valve-seat 3 and the upper valve-seat 5 of the case 1, and the valve is provided with a cylinder 23, preferably provided with a lining 24, into which cylinder projects the cylinder 8, and from the upper end of the valve projects a cylinder 25 and extends down into and is concentric to the cylinder 23 when the valve is resting on its lower seat and concentric to and extends into both the cylinders 23 and 25 when the valve is resting on its upper seat. The cylinder 25 may also be provided with a suitable lining 26, and into this cylinder projects the piston 13, supported on spider 12.

On the lower side of the upper end of the valve, directly under the seat 5, is an annular gear 27, engaged by a pinion 28, connected to a rod 29, provided with a crank 30, for grinding the valve to its upper seat while the valve is in position, (see Fig. 3,) and the pinion, the rod, and the crank are supported in

a bearing 31 in the valve-case, and the lower valve-seat is ground in like manner by a like pinion, rod, and crank (not shown) supported in the lower bearing 32. After the valve 5 has been ground to either seat the pinion 28 is drawn toward the valve-case out of engagement with the gear 27, where it remains until regrinding is required. This invention will form the subject-matter of another application for a patent.

33 indicates a plug-valve to whose case 34 is connected a pipe 35 for supplying fluid from a steam-boiler or other source of supply under high pressure—say one hundred (100) 15 pounds—a pipe 36, leading to the passage in the upper spider, a pipe 37, leading to the passage 10 in the lower spider, and a waste-pipe 38 for relieving the cylinders 23 and 25 in the valve 20. This valve is provided with a rod 20 or stem 39, to which is secured a lever 40 by a key 41 and a lever 42, loose thereon, and having a notch 43, engaged by a dog or latch 43', carried by lever 40 and held normally in engagement with the notch by a spring 44, and 25 the lever 42 is provided with a wrist-pin 45, engaged by a rod 46, connected to the inner end of a lever 47, provided with a weight 48 and fulcrumed on a support 49.

50 indicates an air-chamber attached to and 30 communicating with the condenser-chamber 2 by means of pipes 51 and 52. This chamber is provided with a metallic diaphragm 53, joined to the lever 47 by a connection 54, an air-valve 55, whose stem 56 is attached to the 35 arm 57 of the float 58, which arm is pivotally connected to the wall of the air-chamber to allow the float to rise and fall freely, and a valve 59, also pivotally supported and raised by a pin 60 on the stem 56 to close the inner 40 end of pipe 51 and opened by the counter-weight 61, forming part of the valve.

The operation is as follows: Before starting the condenser the main valve 20 is on its lower seat 3, and when the condenser is started 45 and has produced enough vacuum in the air-chamber 50 underneath the diaphragm 54 to overcome the weight 48 the diaphragm is pushed down by the atmosphere acting on its upper surface and through the rod 46 engaging 50 the lever 42 on the stem 39 of the plug-valve 33 turns said valve and directs water under pressure from the pipe 35, communicating with the boiler into the lower cylinders 8 and 23, which now constitute one continuous 55 cylinder and raise the valve 20 to its upper seat 5, so that the main engine can be started, and its exhaust-steam will flow directly to the condenser-chamber 2 in the usual way. If everything works properly, the valve 60 20 will remain in this position until the end of the day's work, and then when the main engine and the condenser are shut down the vacuum naturally runs down until it gets to a point where the weight 48 will overbalance 65 the pull of the vacuum on the diaphragm 54, when the weight descends and the plug-valve

33 is reversed to its opposite position, releases the water-pressure from the lower cylinder, and directs the water-pressure into the upper cylinder 25, which acting against the piston 70 13 pushes the valve 20 down to its lower seat 3, thus cutting off communication with the condenser and opening the valve to the atmosphere through its upper ports 6. If, however, during the operation of the engine the 75 vacuum should be lost by overloads or leaks or other causes, this loss of vacuum automatically opens the valve 33 in the manner heretofore described, which closes the valve 20 and allows the engine to work non-condensing 80 with absolutely no back pressure and by closing the ports in the main valve at the upper end of the condenser-chamber at the same time prevents the condenser-chamber from becoming hot, as is the case in the usual 85 methods of operation, and, further, as soon as the condenser produces its vacuum again the valve 20 will be raised automatically and direct the exhaust-steam into the condenser and the engine work condensing as before. 90

Should the condenser-chamber 2 become flooded from any cause, the float 58 in the air-chamber 50 will rise, when the water enters through the lower pipe 52, opens the air-valve 55, and closes the valve 59 at the end of 95 the pipe 51, admitting air into chamber 50 underneath the diaphragm 53, and then break or destroy the vacuum in the chamber 50 and reverse the plug-valve 33, which causes the valve 20 to resume its seat 3 and break or destroy the vacuum in the condenser-chamber 2. As the boiler-pressure in ordinary plants is usually above one hundred pounds and as the highest vacuum is only 14.7 pounds, the cylinder 25, holding the valve 20 to its seat, 105 is much smaller in diameter than the valve-seat proper.

The plug-valve 33 may be operated by hand by the use of the lever 40.

Having thus fully described my invention, 110 what I claim is—

1. A valve - case having opposite valve-seats, and a valve having corresponding faces; in combination with means within the valve-case for operating the valve in opposite directions, means for supplying fluid-pressure thereto, and a condenser-chamber.

2. A valve - case having opposite valve-seats, and a valve having corresponding faces; in combination with opposite cylinders within 120 the valve-case, and means for supplying a fluid thereto and a condenser-chamber.

3. A valve - case having opposite valve-seats, and a valve having corresponding faces; in combination with opposite cylinders within 125 the valve-case, a valve for supplying a fluid to said cylinders, and means for automatically operating the fluid-supply valve and a condenser-chamber.

4. A valve-case, a valve, and means within 130 the valve-case for operating the valve by fluid-pressure; in combination with a fluid-

supply valve, and means operated upon by the atmosphere to control the fluid-supply valve and a condenser-chamber.

5. A relief-valve, a condenser-chamber, and

5 a fluid-pressure chamber in communication with the condenser-chamber, and means operated from said pressure-chamber for holding the valve to its seat against the vacuum.

6. A relief-valve, and means for operating

10 the valve by fluid-pressure; in combination with a fluid-supply valve, and an automatically-operated valve-controlling mechanism and a condenser-chamber.

7. A relief-valve, and a condenser-cham-

15 ber; in combination with an air-chamber connected to said condenser-chamber, an air-valve, and a float for operating said valve to destroy the vacuum in said condenser-chamber.

8. A relief-valve, and means for operating

20 said valve by fluid-pressure; in combination with a fluid-controlling valve, and a lever connected to said valve and a condenser-chamber.

9. A relief-valve, and means for operating

said valve by fluid-pressure; in combination

with a fluid-controlling valve, and levers de- 25 tachably connected together and engaging the stem of the operating-valve and a con- denser-chamber.

10. A valve-case having opposite valve- 30 seats, and a valve having corresponding faces, concentric cylinders formed in the valve, and a piston for the inner cylinder, and means for supplying a fluid to said cylinder; in com- bination with a condenser-chamber.

11. A valve-case, a valve having concentric 35 cylinders therein, a cylinder secured to the valve-case and extending into the outer cyl- 40 nder in the valve, a piston secured to the valve-case and extending into the inner cyl- nder in the valve, and means for supplying a fluid to said cylinders; in combination with a condenser-chamber.

In testimony whereof I affix my signature in presence of two witnesses.
